UNITED STATES PATENT OFFICE.

ARCHIBALD D. SCOTT, DECEASED, LATE OF JERSEY CITY, NEW JERSEY; BY MARY V. SCOTT, EXECUTRIX, OF JERSEY CITY, NEW JERSEY, ASSIGNOR TO VARLEY DUPLEX MAGNET COMPANY, A CORPORATION OF NEW JERSEY.

WINDING MACHINE.

Application filed October 31, 1923. Serial No. 671,908.

This invention relates to machines for therefrom. The shaft 2 extends through 55 winding strands of material, such as wire, and is rotatably mounted in the housing 3, thread, ribbon, filaments or the like into coils, helices, or bobbins, and particularly to 5 machines of this type which are utilized for winding copper wire into electric coils or helices for use in various kinds of electrical apparatus. The particular invention herein 10 described and claimed is in the nature of an improvement upon machines of the type illustrated in U. S. Patent 1,368,536 issued February 15, 1921. In the patented machine mentioned, a plurality of coils are wound simultaneously in separate zones upon a 15 spindle or mandrel, the convolutions of wire being wound in layers superposed one upon the other. During the formation of the layers, the wire is guided to the spindle to lie spirally thereon by giving the wire a 20 slight movement endwise of the spindle. It is frequently desirable to lay the wire upon the spindle with a coarser pitch of the spiral turns particularly at the beginning or the 25 ending of the coils. In prior machines this has been either impossible or very difficult to accomplish.

An object of this invention is to provide an improved machine of the character described, with which the pitch of the spiraling of the strands or wire may, in a simple manner, be varied, more particularly increased, to any desired extent at any periods in the formation of the coils, and which will be relatively simple in construction and operation. Other objects and advantages will be apparent from the following description of an embodiment of the invention, and the novel features will be particularly pointed out hereinafter in claims.

40 In the accompanying drawing:

Fig. 1 is a plan of a machine constructed in accordance with the invention;

Fig. 2 is a sectional elevation of a portion of the same, taken substantially along the 45 line 2-2 of Fig. 1; and

Fig. 3 is another sectional elevation of a portion of the machine, taken substantially along the line 3-3 of Fig. 1.

In the illustrated embodiment of the invention, the coils are to be wound in spaced zones upon the winding spindle 1. The spindle is driven by the aligned shaft 2 in a manner permitting removal of the spindle when the completed coils are to be removed

55 carried by the frame 4 of the machine, and is driven from any suitable source of power such as by a belt 5 or equivalent means. The wires or strands to be wound are conducted 60 from suitable supply spools (not shown in the drawings), over and around the guiding pulleys 6 of the guiding devices 7 that are carried by a traverse rod 8. The traverse rod 8 is disposed parallel with the winding 65 spindle and mounted for reciprocation in an endwise direction so that the wires or strands will be fed lengthwise of the spindle while being wound thereon. This causes the wires to be wound upon the winding spindle in 70 spiral form, the layers being superposed upon one another by the reversal of movement of the traverse rod.

A shaft 9 (see Figs. 2 and 3 particularly) is disposed transversely of the driving shaft 75 2, and is rotatably supported in the housing 3. A worm wheel 10 is rotatably mounted upon the shaft 9 within the housing 3, and meshes with a worm screw 11, also within the housing and secured to and rotating with 80 the shaft 2. The worm wheel 10 has a reduced extension 12 which projects through the forward wall of the housing 3 and carries, upon the exterior end thereof, a ratchet wheel 13, the ratchet wheel being secured to the worm wheel extension by a semi-cylindrical key 14 in order to cause rotation of the ratchet wheel with the worm wheel. A hand wheel 15 is secured, in any suitable manner such as by a pin 16, upon the 85 forward end of the shaft 9, the hand wheel having a band flange 17 which embraces the ratchet wheel 13.

A pawl 18 is disposed in a slot 19 of the flange 17, so as to move radially of the flange, and upon its inner edge carries a tooth 20 which is adapted to engage between the teeth 21 of the ratchet wheel. A spring 22, at one end, is anchored to the flange 17, and also thereto at an intermediate point by a support 23. The spring extends peripherally around the flange 17 for some distance, and is attached to or presses upon the pawl 18 so as to yieldingly press the latter laterally toward the teeth 21, and maintain the pawl in engagement with the ratchet wheel. The pawl forms a driving connection in one direction between the worm wheel 10 and the

hand wheel 15, and at the same time permits the hand wheel to rotate in the same direction independently of the rotation of the worm wheel. A pin 24 carried by one of the 5 end walls of the slot 19 engages with a slot 25 in an abutting hand edge of the pawl 18, for guiding the pawl in its movements radially of the end wheel, and preventing lateral displacement relatively thereto.

10 The shaft 9 at its rearmost end carries a bevel gear 26 meshing with a bevel gear 27. The gear 27 forms part of a gear train 28 that operates various cam mechanisms for inserting sheet material between layers of 15 the wire being wound upon the spindle and for reciprocating the traverse rod 8. One of the gears 29 of the gear train 28 acts, through an idler 30, to drive a gear 31 provided upon a cam drum 32. The cam drum 20 is provided with a cam groove cooperating with a follower 33 provided upon the traverse rod 8, so that when the shaft 9 rotates, the traverse rod will be reciprocated in an endwise direction.

25 The details of the mechanism for measuring, cutting, and inserting sheet material between the layers, form no part of the present invention, and a description thereof is omitted for the purpose of simplicity, it 30 being understood that reference may be had to the prior Patent 1,368,536, hereinbefore referred to, for a full disclosure of such details as may be employed.

In the operation of the machine, the form 35 upon which the coils are to be wound is placed upon the winding spindle 1, and the latter placed in the machine, as illustrated in Fig. 1, in driving relation with the shaft 2. The strands of wire or other material 40 are conducted from the pulleys 6 of the guide devices 7 and attached to the form upon the winding spindle, it being understood that the guide devices are spaced along the traverse rod in accordance with the desired 45 spacing between the coils to be wound.

When the machine is started, the belt 5 will rotate the shaft 2 and through it the winding spindle 1. The winding spindle in 50 rotating will draw upon the wire or strands, and the latter will be wound around the form upon the spindle. At the same time the worm 11 on the shaft 2 will drive the worm wheel 10 and the latter through the pawl 18 will drive the hand wheel 15 which 55 is fixed to the shaft 9. The shaft 9 through the gear drive 28 will rotate the cam drum 32 and cause reciprocations of the traverse rod 8. The reciprocations of the traverse 60 rod will cause the strands of wire to be laid spirally upon the form on the winding spindle, the direction of the spiralling being changed at the reversals of travel of the traverse rod, so as to form superposed layers in each coil being wound. The gear train 65 28 also actuates the other mechanism for

measuring, cutting, and inserting strips of sheet insulating material between the layers formed upon the winding spindle. After the desired number of layers or turns of wire have been placed upon the 70 form carried by the winding spindle, the machine is stopped.

It is frequently desirable to produce a number of layers, each having a definite spiral formation, and then to provide a number of turns in a different, such as a coarser 75 spiral formation. To effect this different or coarser spiral formation, the machine after the other layers have been formed and the machine has been stopped, is allowed to remain idle, that is, with the power cut off, and the operator manually turns the hand wheel 15 in its normal operating direction, at the same time manually rotating the driving shaft 2 or spindle 1. In this manner the 80 shaft 9 will be operated at a different ratio, relatively to the winding spindle, than in the normal operation of the machine, which causes the traverse rod to move at a different 85 rate, relatively to the rotation of the winding spindle. By this different movement of the traverse rod the spiralling of the turns of wire upon the winding spindle will be different. After the desired different spiralling of the turns has been effected, the winding 90 spindle and coils may be removed, or additional layers placed thereon as desired. In case it is desired, for example to lay the turns of wire in a coarse spiral relation at the beginning of the coils, the hand wheel 100 15 and the driving shaft 2 will both be operated manually to the desired extent before the machine is driven by its source of power in the usual manner. It will be observed that it is unnecessary to make any 105 connections or disconnections of the various parts of the machine in order to enable the operator to apply the coarser spiralling of the wire at any period in the formation of the coils and the machine is at all times 110 ready for operation instantly in the usual manner. It will also be observed that the spiralling of the turns of wire or strand, may be greater or less in pitch, during 115 manual operation but, in the construction shown in the drawings, it will be greater than during the normal power operation of the machine.

It will be obvious that various changes in the details and arrangements of parts, herein described and illustrated for the purpose of explaining the nature of the invention, may be made by those skilled in the art within the principle and scope of the invention as expressed in the appended claims. 120

Claims:

1. In a winding machine, a winding spindle, means for rotating said spindle, a guide for conducting to the spindle the material to be wound thereon and shiftable in 125

directions endwise of the spindle to cause the material to be wound thereon in spiral form, means for causing repeated back and forth movements of the guide to form superposed layers of the material, and a geared driving connection comprising only rotatable elements including intermeshing gear wheels between the last named means and the spindle rotating means for effecting their normal concomitant operation, said connection including therein a rotatable driving member, a rotatable driven member, a one way clutch for normally driving the latter member from the former, and an operating member enabling manual operation of the guide moving means more rapidly than its normal operation with the spindle rotating means whereby the material may, when desired, be laid in a coarser spiral than that laid in its normal operation.

2. In a winding machine, a winding spindle, a driving shaft to which the spindle may be connected for operation, means for guiding to the spindle the material to be wound thereon and operable in directions endwise of the spindle to cause the material to be wound upon the spindle in spiral form, means for causing repeated back and forth movements of the guiding means to form superposed layers of the material, and driving mechanism between the last named means and the driving shaft including a shaft having a geared connection to said driving shaft, with a cooperating ratchet and spring pawl included in the connection to permit of operation of the guiding means at a rate in excess of its normal rate, relatively to its driven connection with the spindle driving shaft, and cause a coarser spiraling of the material wound on said spindle.

3. In a winding machine, the combination of a winding spindle, a movable guide for directing to the spindle the material to be wound thereon, means for moving the guide back and forth along the spindle to cause the material to be wound thereon in spiral form in superposed layers, a rotatable driving member for the spindle having repeated unidirectional rotation, a rotatable operating member for said guide-moving means, and a continuously acting driving connection between said members for normally continuously repeatedly unidirectionally rotating said operating member from said driving member including a normally constantly engaged rotatable one way clutch which normally continuously repeatedly rotates unidirectionally as a unit and pro-

vides for rotating said operating member in its normal direction at a rate above normal relatively to the driving member for thereby increasing the pitch of the spiral winding at any place therein desired.

4. In a winding machine, the combination of a winding spindle, a movable guide for directing to the spindle the material to be wound thereon, means for moving the guide back and forth along the spindle to cause the material to be wound thereon in spiral form in superposed layers, a rotatable driving member for the spindle having repeated unidirectional rotation, a rotatable operating member for said guide-moving means, a continuously acting driving connection between said members for normally continuously repeatedly unidirectionally rotating said operating member for said driving member including a normally constantly engaged rotatable one way clutch which normally continuously repeatedly rotates unidirectionally as a unit and provides for rotating said operating member in its normal direction at a rate above normal relatively to the driving member for thereby increasing the pitch of the spiral winding at any place therein desired, and manual means for thus rotating said operating member at its said rate above normal.

5. In a winding machine, in combination, a rotatable spindle member to effect the winding of strand-like material thereon, a movable guide for directing such material to the spindle, means for moving the guide back and forth along the spindle to cause the material to be wound thereon in spiral form in superposed layers, a rotatable operating member for said guide-moving means, and rotatable means in common for normally continuously repeatedly rotating both of said members concomitantly, said means including a normally constantly engaged rotatable one way clutch normally repeatedly rotating unidirectionally as a unit and forming a continuously acting driving connection for normally continuously repeatedly unidirectionally rotating one of said members and to permit said clutch-driven member to be rotated in its normal direction at a rate higher than normally relatively to the rotation of the other said member for thereby varying the pitch of the spirally wound material when desired.

In witness whereof, I hereunto subscribe my signature.
